UNITED STATES PATENT OFFICE.

ELMER LINDSLEY, OF THE UNITED STATES ARMY.

DESIGN FOR A POCKET-KNIFE.

SPECIFICATION forming part of Design No. 31,173, dated July 11, 1899.

Application filed December 26, 1896. Serial No. 617,104. Term of patent 3½ years.

To all whom it may concern:

Be it known that I, ELMER LINDSLEY, a lieutenant in the sixth cavalry, United States Army, stationed at Fort Yellowstone, in the Yellowstone Park, State of Wyoming, have invented and produced a certain new and original Design for a Pocket-Knife; and I do hereby declare the following to be a full, clear, and exact description of the invention, such as will enable others skilled in the art to which it appertains to make and use the same.

My design consists, essentially, of a pocket-knife comprising the following characteristics, viz: a handle having a large cylindrical portion A, with a flange *a* at one end, and a shorter reduced portion B, connected to the portion A by a suddenly-tapering interme-

diate portion C, a cylindrical shank D, of slightly smaller exterior diameter than the reduced portion B of the handle, the said cylindrical shank having a flat end *d*, and a blade E, extending axially from the flat end of said shank, as shown in the accompanying drawing, which represents a perspective view of a pocket-knife embodying my design. 25

What I claim as my invention is—

The design for a pocket-knife, substantially as herein shown and described.

In testimony whereof I affix my signature in presence of two witnesses.

ELMER LINDSLEY.
